UNITED STATES PATENT OFFICE

117,329

DESIGN FOR A LAUNDRY TUB

Olof S. Burman, Minneapolis, Minn.

Application March 13, 1939, Serial No. 83,553

Term of patent 14 years

To all whom it may concern:

Be it known that I, Olof S. Burman, a citizen of the United States, residing at Minneapolis, in the county of Hennepin and State of Minnesota, have invented a new, original, and ornamental Design for a Laundry Tub, of which the following is a specification, reference being had to the accompanying drawing, forming part thereof.

Fig. 1 is a front perspective view of a laundry tub showing my new design; and

Fig. 2 is a rear perspective view thereof.

The dominant feature of the design is the inwardly projecting, tub overlapping soap tray or shelf of the appearance and configuration illustrated.

I claim:

The ornamental design for a laundry tub, as shown and described.

OLOF S. BURMAN.
